DRAFT CONTROL

Thomas A. Gerlach, Harvey, Ill.

Application November 20, 1931, Serial No. 576,239

11 Claims. (Cl. 236—45)

My invention relates to draft regulators and more particularly to a combination draft regulator and check draft.

The object of my invention is to make a simple and inexpensive device which will automatically provide a uniform predetermined draft in a furnace or stove regardless of the condition of the weather outside.

In addition, it is also the purpose of this invention to provide a device of this character which will serve in the place commonly used for check dampers for furnaces and will be more efficient than such dampers in that the amount of checking applied is automatically dependent on the condition of the weather and the amount of fire in the furnace, closing as the fire goes down and opening as the fire comes up. The device is also arranged so that it may be regulated manually when the weather or the amount of fire in the furnace will not affect its action.

Another particular purpose of the invention is to provide a device of this character wherein automatic draft regulation is obtained by means of a floating disk and a guide member without the addition of a weight or lever of any kind.

I will describe the preferred form of my invention by reference to the accompanying drawing wherein—

Fig. 1 is a longitudinal section through the draft regulator illustrating the manner in which it operates when attached to the furnace;

Fig. 2 illustrates the positioning of the regulator to adjust it for variations in furnace or weather conditions;

Fig. 3 illustrates the extreme position of the regulator in which it no longer functions as a stabilizer.

Referring now in detail to the drawing, the numeral 5 indicates an inlet pipe which leads to the furnace stack stove pipe or other outlet conduit for furnace gases. The numeral 6 refers to a casing which, as shown, has an outlet opening at 7 into the connecting pipe 5 which is usually very short and which may be a part of the furnace chimney or flue. The casing has at the bottom thereof a round opening 8 through which the air may enter, and, after passing upwardly through the baffle member 9, the air may pass through the outlet 7 to the chimney.

It is well known that as the fire temperature increases there is a tendency for a higher speed of gas and a lower pressure of gas in the outlet conduit or chimney. Moreover, sudden gusts of wind or high wind storm conditions may change the atmospheric pressure around the fur-

nace so that it is difficult to maintain a proper relation between the air pressure at the outlet of the furnace and the air pressure around the furnace which is the same as that at the inlet.

The baffle member 9 as shown is an annular cone shaped member increasing in diameter toward the top, and centrally disposed with respect to this member is a guide rod 10. This guide rod 10 serves to guide a floating disk 11 which is free to move up and down on the guide rod 60 from the lowermost position shown in dotted lines in Fig. 1 to any height up to the top of the casing. This disk being free to rise as the pressure increases on the lower surface thereof will during the normal operation of the furnace rise and fall 65 in response to changes in difference in pressure between the chimney and the atmosphere. As it rises, the disk 11 allows more air to enter the chimney and thus reduces the draft so as to compensate for the excess pressure which caused it 70 to rise.

Thus I have provided a very simple regulating device which is fully automatic in its operation and does not require the use of any weights or levers of any sort.

The guide rod is held at the bottom by a cross bar shown at 12. This rod is also screw-threaded to receive the lock nut 13 and to receive the control disk 14 which may be moved up or down relative to the opening at 8 so as to vary the total 85 amount of air that may enter through the opening 8. The disk 14 is preferably itself screw-threaded onto rod 10, and nut 15 is merely a lock nut which can be jammed against it to prevent its being turned accidentally and thus being 90 thrown out of adjustment.

The cone-shaped member 9 in addition to acting as a regulator on the amount of air it admitted to the chimney also acts as a baffle to prevent soot and dust from the chimney as well as 95 the excessive heat from impairing the free working of the damper 11 on the guide rod.

It will be noted that the casing 6 is swivelly mounted upon the member 5 by means of the sleeve 16 and flanges 17, 18, and 19 so that this casing may be turned to move the axis of the guide rod 10 from a vertical position to any desired tilted position.

The purpose of this mounting is to permit the rotation of the casing to the proper position to 105 give the proper draft regulation for any furnace. That is to say, by rotating the casing into the position shown in Fig. 2 or any intermediate position the guide rod is caused to be inclined so that the weight of the disk 11 no longer offers 110

so much resistance to changes in pressure on the opposite sides thereof. More specifically, when the casing is in the position shown in Fig. 2, the disk will move upwardly for a less difference in pressure than it will in the position shown in Fig. 1. In this way, the draft regulator may be adjusted to the proper draft for different chimneys or for the same chimney at different times.

When the guide rod is in the horizontal position shown in Fig. 3 or nearly so, the damper opens widely, and the device then acts as a check draft. When the device is used as a draft stabilizer only, the control chain 20 and the counter-weight 21 are omitted entirely, and the floating disk 11 bobs up and down due to the change in velocity of wind or other causes so that the draft of the furnace remains almost uniform. The lower disk 14 can be moved up or down to accommodate the total air float for different furnaces, and, then by tilting the casing, it may be adjusted for any desired draft of the furnace.

From the above description, it is believed that the construction and advantages of this device will be clear to those skilled in this art and the advantages thereof readily apparent.

Having thus described one specific form of my invention, what I claim as new and desire to secure by Letters Patent is:

1. In a draft regulator, a casing for attachment to the furnace outlet conduit or stack, said casing opening into said conduit and also having a downwardly directed opening to atmosphere, a floating disk in said casing movable toward and away from said opening, and a rigid guide means 30 for guiding said disk toward and away from said opening, said casing having therein an annular baffle rising about said opening, said baffle permitting more air to enter as the disk rises.

2. In a furnace draft regulator, a casing having an opening into the furnace outlet conduit, and having a bottom opening, a baffle surrounding said opening and projecting up into said casing whereby to retard the backflow of ashes and gas to said opening, and a draft regulating disk within said baffle.

3. In a furnace draft regulator, a casing having an opening into the furnace outlet conduit, and having a bottom opening, a baffle surrounding said opening and projecting up into said casing whereby to retard the backflow of ashes and gas to said opening, and a draft regulating disk within said baffle, said casing having a guide rod for said disk.

4. In a furnace draft regulator, a casing having an opening into the furnace outlet conduit, and having a bottom opening, a baffle surrounding said opening and projecting up into said casing whereby to retard the backflow of ashes and gas to said opening, and a draft regulating disk within said baffle, said casing having a guide rod for said disk, and said rod running down through said opening and being provided below said opening with means for regulating the amount of air inflow through said opening.

5. In a furnace draft regulator, a casing having an opening into the furnace outlet conduit, and having a bottom opening, a baffle surrounding said opening and projecting up into said casing whereby to retard the backflow of ashes and gas

to said opening, and a draft regulating disk within said baffle, said casing having a guide rod for said disk, said casing being movable to tilt said rod relative to the vertical.

6. In a furnace draft regulator, a casing having an opening into the furnace outlet conduit, and having a bottom opening, a baffle surrounding said opening and projecting up into said casing whereby to retard the backflow of ashes and gas to said opening, and a draft regulating disk within said baffle, said baffle expanding in circumference above said opening.

7. In a furnace draft regulator, a casing having an opening into the furnace outlet conduit, and having a bottom opening, a baffle surrounding said opening and projecting up into said casing whereby to retard the backflow of ashes and gas to said opening, and a draft regulating disk within said baffle, said baffle gradually expanding outwardly from said opening to its upper edge.

8. In a furnace draft regulator, a casing having an opening into the furnace outlet conduit, and having a bottom opening, a baffle surrounding said opening and projecting up into said casing whereby to retard the backflow of ashes and gas to said opening, and a draft regulating disk within said baffle, said baffle extending substantially to the top of the opening to the furnace.

9. In a furnace draft regulator, a casing having an opening into the furnace outlet conduit, and having a bottom opening, a baffle surrounding said opening and projecting up into said casing whereby to retard the backflow of ashes and gas to said opening, and a draft regulating disk within said baffle, said casing having a guide rod for said disk, said casing being pivotally mounted whereby said guide rod may be moved between horizontal and vertical position.

10. A draft regulator for furnaces comprising means providing an air inlet to the furnace outlet, a casing covering said inlet and rotatable on said means, said casing having an air inlet at substantially right angles to its axis of rotation, said casing also having a disk therein overlying said inlet and movable bodily toward and away from said inlet in response to fluctuations in draft, guide means in the casing for guiding said disk in its movement toward and away from the inlet, rotation of said casing upon its axis operating to vary the direction of movement of the disk with respect to the horizontal.

11. A draft regulator for furnaces comprising means providing an air inlet to the furnace outlet, a casing covering said inlet and rotatable on said means, said casing having an air inlet at substantially right angles to its axis of rotation, said casing also having a disk therein overlying said inlet and movable bodily toward and away from said inlet in response to fluctuations in draft, guide means in the casing for guiding said disk in its movement toward and away from the inlet, rotation of said casing upon its axis operating to vary the direction of movement of the disk with respect to the horizontal, said casing having means for varying the flow of air into the casing through its inlet for any position of the disk.
